APPARATUS FOR CAPPING BOTTLES

Lydia B. Koch, New York, N. Y., assignor to
Reinforced Paper Bottle Corporation, New
York, N. Y., a corporation of Delaware

Application September 17, 1934, Serial No. 744,356

2 Claims. (Cl. 226—86)

This invention relates to apparatus for and method of capping bottles.

Among the principal objects which the present invention has in view are:—To provide an improved apparatus for capping bottles and the method of doing the same; to form the cap directly in place; to enable the cap to seal tightly within the neck of the bottle; to provide a cap completely formed on the bottle with a sunk portion within the bottle; to provide a tool for performing the cap forming and applying operation; to obtain both the forming and the capping operation with successive movements on the part of the operator; to provide for using the tool with bottles of different height; and to obtain other advantages and results.

In the drawings:

Figure 1 is a vertical elevation of the apparatus for capping bottles embodying my invention;

Figure 2 is a vertical section shown as taken on line 2—2 of Figure 1;

Figures 3 and 4 are similar views and showing successive steps of applying the cap to the bottle;

Figure 5 is a blank disk;

Figure 6 is a similar view and showing the same as operated upon in Figure 4;

Figure 7 is a similar view and showing the same as operated upon in Figure 2;

Figure 8 is an elevation of the completed cap; and

Figure 9 is a sectional view shown as taken on line 9—9 of Figure 7.

As seen in the drawings the cap forming and applying mechanism is shown generally as an upright standard 10 carried by a base 11 and having an adjustable table 12 upon which to support the bottle or similar container 13 which is to be capped. At an upper part of the standard 10 is mounted an adjustable bracket 14 within which is carried a vertically slidable rack 15 operable by a lever 16 fast with respect to a pinion 17 in mesh with the rack.

The cap forming and applying die is partly carried at the lower end of the rack 15, above the table and movable toward the table as will readily be appreciated by those skilled in the art. For this purpose, there is shown a plate 18 at the bottom of rack 15, said plate having near its periphery a plurality of depending rods 19 the lower ends of which are secured to and support a squeezing ring 20. The said ring includes within the same another portion of the die, the body 21 of which is rigidly carried by bracket 22 from the standard 10. This body provides suitable

curvilinear sockets 23 for receiving and retaining the upper ends of fingers 24, said fingers depending through the ring and arranged side by side in a circular formation. Each finger is normally urged outward by a spring 25 between it and said body 21.

The said body 21 is furthermore axially hollow at its lower part and provides therein a plunger head 26 which may conveniently have a sleeve 27 projecting upwardly therefrom into the axial opening 28 of the said body portion for guiding said plunger head. The plunger head is urged normally to its lowermost position by a spring 29 within the sleeve, and downward movement is limited in suitable manner as by a headed stem 30.

The plunger head first engages a disk blank 31 laid upon the top of the bottle and holds the same as the bottle is forced upwardly as by means of a lever 32 operating through a pinion 33 and rack 34 depending from the table through its supporting bracket 35. When the plunger head is seated as far upward within body 21 as it will go, continued raising of the table forces the lower end of said body with plunger head 26 into the neck of the bottle, carrying the subtended part of the disk into the bottle, thus providing the sunken portion 36 of the cap.

By properly shaping the lower peripheral edge of the said body 21, the sunken portion of the cap may be caused to fit tightly within the neck of the bottle. When this operation is completed, the upper lever 16 is swung down, thereby lowering the ring 20 and squeezing fingers 24 inwardly, thus capping the bottle while the forming portion 35 of the die is still within the sunken portion of the cap. A tight seal is therefore maintained between the sunken portion and the bottle while the edge of the cap is formed around the upper edge of the bead of the bottle.

I claim:

1. An apparatus as characterized comprising a standard having a base, a slideable table adjacent said base for holding a bottle, said bottle having a cap thereon, a bracket extending from the standard and supporting the table and bottle, means for raising said table and bottle from said supporting bracket, said means comprising a rack depending downwardly from said table, a pinion mounted in the bracket and juxtaposed to said rack, a hand lever for operating the pinion and rack when raising the table and bottle, means mounted on the standard towards the top thereof for pressing the cap into the neck of the bottle as the table and bottle are fully raised, said means

comprising a bracket extending from the standard and in parallel relationship to the said first bracket, said bracket having a rack and pinion therein and a hand lever for operating the same,
5 said rack having at its lower end and secured thereto a circular plate, said plate adjacent its periphery having a plurality of depending rods for exerting a downward pressure, said rods secured to and supporting a ring, and said ring
10 having therein a die providing means for shaping the cap to the bottle when the said lever lowers the said plate, rod and the ring whereby when lowered will engage the outer edge of the cap and seal the same to the upper outer edge of the neck
15 portion of said bottle.

2. An apparatus as characterized comprising a standard having a base, a slidable table adjacent said base for holding a bottle, said bottle having a cap thereon, a bracket extending from the
20 standard and supporting the table and bottle, means for raising said table and bottle from said supporting bracket, said means comprising a rack depending downwardly from said table, a pinion mounted in the bracket and juxtaposed to said
25 rack, a hand lever for operating the pinion and rack when raising the table and bottle, means mounted on the standard towards the top thereof for pressing the cap into the neck of the bottle

as the table and bottle are fully raised, said means comprising a bracket extending from the standard and in parallel relationship to the said first bracket, said bracket having a rack and pinion therein and a hand lever for operating the same,
5 said rack having at its lower end and secured thereto a circular plate, said plate adjacent its periphery having a plurality of depending rods for exerting a downward pressure, said rods secured to and supporting a ring, and said ring
10 having therein a die providing means for shaping the cap to the bottle when the said lever lowers the said plate, rod and the ring whereby when lowered will engage the outer edge of the cap and seal the same to the upper outer edge of the neck portion of said bottle, and said die means comprising a bracket extending from the standard and parallel to the said other brackets, the said bracket rigidly supporting a body member,
15 said body member being stationary and having a plurality of curvilinear sockets, a plurality of fingers depending downwardly therefrom and adapted to be retained in place by the ring whereby when the ring is lowered the said fingers at their lower ends will clamp the outer peripheral edge of the cap against underside of the outer edge of the said neck portion of the bottle.
LYDIA B. KOCH.
